(57) **CLAIM**

(**) Term: **15 Years**

The ornamental design of a rise centered sunrise alarm clock
as shown and described.

(21) Appl. No.: **29/902,554**

DESCRIPTION

(22) Filed: **Sep. 14, 2023**

FIG. 1 shows a top perspective view of a front side of a rise
centered sunrise alarm clock according to the present invention;

(51) LOC (15) Cl. **10-01**

FIG. 2 shows a front view of the rise centered sunrise alarm
clock shown in FIG. 1;

(52) U.S. Cl.

FIG. 3 shows a back view of the rise centered sunrise alarm
clock shown in FIG. 1;

USPC **D10/5**; D10/15

FIG. 4 shows a side view of one side of the rise centered
sunrise alarm clock shown in FIG. 1, where the other side is
a mirror image of the one side shown in FIG. 4; and

(58) **Field of Classification Search**

FIG. 5 shows a top view of the rise centered sunrise alarm
clock shown in FIG. 1; and,

USPC D10/1-3, 5, 15, 22, 24, 28, 40-41;
D26/51, 52, 54, 34, 115
CPC G04G 13/00; G04G 13/02; G04G 13/028;
G04G 17/086; G04G 21/08; G04G 9/00

FIG. 6 shows a bottom view of the rise centered sunrise
alarm clock shown in FIG. 1.

See application file for complete search history.

The broken lines in the Figures of the drawing illustrate
portions of the article that form no part of the claimed
design.
